(57) **CLAIM**

The ornamental design for a cooking vessel, as shown and described.

DESCRIPTION

FIG. 1 is an exploded front perspective view of the three items, identified as item 1, item 2, and item 3, that form the cooking vessel;

FIG. 2 is an exploded rear perspective view thereof;

FIG. 3 is a front perspective view thereof with the three items combined;

FIG. 4 is a rear perspective view thereof with the three items combined;

FIG. 5 is a front view thereof with the three items combined;

FIG. 6 is a top view thereof with the three items combined;

FIG. 7 is a cross-sectional view along line 7-7 of FIG. 6;

FIG. 8 is a cross-sectional view along line 8-8 of FIG. 6;

FIG. 9 is a front view of item 1;

FIG. 10 is a rear view of item 1;

FIG. 11 is a top view of item 1;

FIG. 12 is a bottom view of item 1;

FIG. 13 is a left side view of item 1;

FIG. 14 is a right side view of item 1;

FIG. 15 is a front view of item 2;

FIG. 16 is a rear view of item 2;

FIG. 17 is a top view of item 2;

FIG. 18 is a bottom view of item 2;

FIG. 19 is a left side view of item 2;

FIG. 20 is a right side view of item 2;

FIG. 21 is a front view of item 3;

FIG. 22 is a rear view of item 3;

FIG. 23 is a top view of item 3;

FIG. 24 is a bottom view of item 3;

FIG. 25 is a left side view of item 3; and,

FIG. 26 is a right side view of item 3.

The broken lines in the various figures form no portion of the claimed design.
